UNITED STATES PATENT OFFICE

1,927,998

TENTER CLIP

John H. Williams, Providence, R. I.

Application May 27, 1932. Serial No. 613,987

1 Claim. (Cl. 26—62)

This invention relates to improvements in tenter machine apparatus and is directed more particularly to improvements in web engaging clips used for the chains of tenter machines.

8 The principal objects of the invention are directed to improvements in tenter clips and as will further appear the novel features of the invention reside in a novel combination and arrangement of the parts whereby the clip is adapted for 10 long life and may be manufactured at a small cost while at the same time the clip is adapted for the most efficient operation.

As is well known, a tenter machine includes a pair of endless chains formed from pivoted together clips adapted to engage opposite marginal edges of a web of cloth or the like so that the web may be carried forwardly through the tenter machine by the adjacent inner runs of the chains. The clips consist in general of plates upon which 20 the web rests and jaws or gates pivoted thereabove which bear on the web to hold it on the plate. In that way the web is gripped.

According to special features of this invention there is provided a tenter clip wherein the 25 jaw is provided with a web engaging plate member arranged for movements in the jaw so that the member may align with the plate or bear evenly thereon. The said member has a substantial bearing in the jaw to support the same in 30 a rigid manner and yet allow the member to tilt as is necessary for the best operation of the clip. This is accomplished by providing a substantial bearing between the plate and jaw to permit relative movements thereof while separate means is 35 provided to hold the plate and jaw against separation beyond a certain limit of desired relative movements.

Various novel features and advantages of the 40 invention will appear from the following description of the preferred form thereof. For purposes of disclosure the preferred form of the invention is shown in the accompanying drawing, wherein:

45 Fig. 1 is a side elevational view of a tenter clip embodying the novel features of the invention.

Fig. 2 is a front elevational view of a clip jaw or gate shown in Fig. 1.

50 Fig. 3 is a front elevational view showing the jaw plate of the invention.

Fig. 4 is a transverse sectional view taken on the line 4—4 of Fig. 3, and

55 Fig. 5 is a similar view taken on the line 5—5 of Fig. 2.

Referring now to the drawing more in detail the invention will be fully described.

In Fig. 1 there is shown a tenter clip C having a web supporting plate P for underlying and supporting the side marginal edges of a web. A 63 jaw or gate G is pivoted to arms 4 above the plate P and is adapted to swing inwardly or to the left from the position shown in Fig. 1. The lower end of the jaw is adapted to rest on a web supported by the plate P and hold the web against 65 being pulled to the right.

The lower end of the gate is slotted as at 9 throughout its length and a plate 8 which may be called a jaw plate is carried in said slot so as to be movable therein as will later appear. 70

In the manufacturing of the jaw G the slot 9 may be formed therein by a cutter such as a rotary cutter or the like. For best results the width of the slot 9 will be slightly greater than the thickness of the jaw plate member 8 so that the 75 member 8 may move in the slot 9 more or less freely as is desired.

A curved seat 10 is provided intermediate the ends of the slot 9 which may be on the radius of a circle and preferably according to the invention the radius of the curve will be sufficiently large to form a circular seat of considerable length relative to the length of the jaw as is shown. 80

The plate 8 on its upper side has a curved or circularly formed bearing surface 11 of the contour to bear on the seat 10 as shown in Fig. 2.

Pins or rivets 12 carried by the jaw G, at either side of the seat 10 pass through openings 14 provided in the member 8. These pins are suitably held in the jaw and prevent the plate member 8 from falling from the slot 9. They are not intended as pivots for the plate 8 but merely to hold the plate 8 in the jaw and allow the plate to move. 90

The openings 14 are considerably larger than the rivets or pins 12 or at least are larger than the shanks 13 of said pins so that the ends of the member 8 may move up and down relative to the jaw member while the portion 11 of the plate 8 bears on the seat 10. This is so the lower edge of the member 8 may align with the plate or adjust itself to the plate and an edge of a web resting on said plate. In this way the member 8 may at all times bear on a web or the plate throughout its length and adjust itself to non-aligned conditions. 95

By reason of the curved surface of the member 8 bearing on the seat 10 the member 8 may tilt or swing while it is held by pins 12 against dropping from the jaw. 100

By providing the relatively long seat 10 and the 110

relatively long curved edge portion 11 of the member 8 there is a substantial bearing support between the plate member and the jaw so that the jaw may act on the member 8 with considerable pressure as is often necessary.

As distinguished from merely pivoting the member 8 to the jaw where there would be relatively small bearing surface between the parts there is in this case a substantial bearing surface 10 so as to reduce wear and give strength. There is no wearing action on the pins 12 and the openings 14 of the jaw plate so that the construction has a life appreciably longer than a conventional type of tenter clip.

15 Having described the invention in the form at present preferred what I desire to claim and secure by Letters Patent of the United States is:

20 A tenter clip comprising in combination, a gate pivoted for swinging movements so its lower edge lies above a web supporting plate, the said gate being provided with a slot extending upwardly from said lower edge to provide a continuous U-shaped section having front and rear walls and a continuous closed bottom wall for said slot ex-

tending from end to end of said gate, the bottom wall of the slot being provided with a curved seat portion intermediate its ends formed on a radius the axis of which is located beyond the lower edge of the jaw, a jaw plate movable in said slot 80 having a curved edge portion intermediate its ends which is complementary to and adapted to bear against the curved seat portion of the bottom wall and having longitudinal edges at either side thereof normally out of contact with the bottom wall of the slot at either side of the curved seat portion, pins passing through the front and rear walls of said jaw extending through said slot adjacent the ends thereof at either side of the curved seat portion of the slot and the said 85 plate being provided with openings receiving the pins which are relatively larger and normally out of contact with said pins, all adapted and arranged whereby the curved edge portion of the plate may bear in the curved seat portion of the bottom wall of the slot and may freely tilt in said slot independently of said pins.
